Des. 228,583
Patented Oct. 16, 1973

228,583

SPORT GOGGLES

Conrad Leblanc, 33 Bartlett St.,
Leominster, Mass. 01453

Filed Aug. 25, 1971, Ser. No. 175,014

Term of patent 14 years

Int. Cl. D2—03

U.S. Cl. D2—234

FIG. 1

FIG. 2

FIG. 3

FIG. 4

FIG. 1 is a front elevational view of sport goggles showing my new design;

FIG. 2 is a side elevational view thereof;

FIG. 3 is a front perspective view thereof; and

FIG. 4 is a rear perspective view thereof.

The side not shown has substantially the same appearance as the side shown.

I claim:

The ornamental design for sport goggles, substantially as shown and described.
